(57) **CLAIM**

The ornamental design for the halter for personal item carrier, as shown and described herein.

DESCRIPTION

FIG. 1 illustrates a top, front, right-side perspective view of a halter for personal item carrier of my new design.

FIG. 2 illustrates a front elevation view thereof.

FIG. 3 illustrates a rear elevation view thereof.

FIG. 4 illustrates a left-side elevation view thereof; and,
FIG. 5 illustrates a right-side elevation view thereof.

The broken lines immediately adjacent the shaded areas represent the bounds of the claim and all other broken lines are for illustrative purposes only. None of the broken lines form a part of the claimed design.

The broken lines shown on the strap surfaces represent conventional stitching.
